Primary Examiner — Catherine R Oliver-Garcia
(74) Attorney, Agent, or Firm — K&L Gates LLP

(57) **CLAIM**

The ornamental design for a fishing lure, as shown and described.

DESCRIPTION

FIG. 1 is an isometric view of a fishing lure showing my new design;

FIG. 2 is a front elevation view of the fishing lure of FIG. 1;

FIG. 3 is a back elevation view of the fishing lure of FIG. 1; FIG. 4 is a left side elevation view of the fishing lure of FIG. 1;

FIG. 5 is a right side elevation view of the fishing lure of FIG. 1;

FIG. 6 is a plan view of the fishing lure of FIG. 1;

FIG. 7 is a bottom plan view of the fishing lure of FIG. 1; FIG. 8 is an isometric view of a further embodiment of the fishing lure showing my new design;

FIG. 9 is a front elevation view of the fishing lure of FIG. 8;

FIG. 10 is a back elevation view of the fishing lure of FIG. 8;

FIG. 11 is a left side elevation view of the fishing lure of FIG. 8;

FIG. 12 is a right side elevation view of the fishing lure of FIG. 8;

FIG. 13 is a plan view of the fishing lure of FIG. 8; and, FIG. 14 is a bottom plan view of the fishing lure of FIG. 8. The broken lines depict portions of the fishing lure that form no part of the claimed design.

1 Claim, 8 Drawing Sheets
